UNITED STATES PATENT OFFICE.

JULIUS C. HERRMANN, OF ST. LOUIS, MISSOURI, ASSIGNOR TO AMERICAN CAR & FOUNDRY COMPANY, OF ST. LOUIS, MISSOURI, A CORPORATION OF NEW JERSEY.

CAR-DOOR-OPERATING MECHANISM.

No. 823,863.

Specification of Letters Patent.

Patented June 19, 1906.

Application filed January 2, 1906. Serial No. 294,240.

To all whom it may concern:

Be it known that I, JULIUS C. HERRMANN, a citizen of the United States, residing at St. Louis, Missouri, have invented a certain new and useful Improvement in Car-Door-Operating Mechanism, of which the following is a full, clear, and exact description, such as will enable others skilled in the art to which it appertains to make and use the same, reference being had to the accompanying drawings, forming part of this specification, in which—

Figure 1 is a plan view of a portion of a car, showing my improved door-operating mechanism; Fig. 2 is a vertical sectional view through the car, showing the door-operating mechanism in position thereon; and Fig. 3 is a side elevational view of said mechanism.

This invention relates to a new and useful improvement in mechanism for operating the doors of cars.

The objects of this invention are to simplify the construction of door-operating mechanism and at the same time provide a construction which will enable the operator to open or close the doors on the opposite sides of the center sill by the movement of a hand-wheel.

With these objects in view the invention consists in the construction, arrangement, and combination of the several parts, all as will be hereinafter described and afterward pointed out in the claims.

In the drawings, 1 indicates the side walls of a car, 2 is the floor thereof, and 3 represents the center sills. Suitable brackets extend from the side walls and provide bearings of a shaft 4, at one end of which is arranged a hand-wheel 5. The shaft 4 instead of being provided with a hand-wheel may have a squared end portion to permit the use of a wrench, whereby power may be imparted to the shaft 4.

6 indicates a ratchet-wheel on the shaft 4, with which ratchet-wheel co-operates a pawl 7. On the inner end of shaft 4 is a pinion 8, said pinion meshing with a gear 9, arranged on a shaft 10, said shaft 10 finding bearings in suitable depending brackets secured to the side walls and center sills of the car. 11 represents rock-arms fixed to shaft 10, which rock-arms are connected to links 12, which links carry at their opposite ends a shaft 13, there

preferably being a shaft 13 under each door. The ends of shaft 13 carry rollers 14, which co-operate with inclined tracks 15, supported from the side walls and center sills of the car, respectively, said tracks 15 being preferably inclined, as shown in Fig. 3, the highest portions of each track also having a horizontal portion on which the roller 14 rests when the door is closed. Shafts 13 also carry rollers 16, which co-operate with flanged plates 17, depending from the doors 18, the lower flanges of said plates constituting bearing-surfaces for co-operating with the rollers 16. When the doors are closed, the rollers 16 lie under the flat portions of the bearing-surfaces, which flat portions are substantially parallel to the door-panels. The bearing-surface recedes toward the hinged edge of the door, so as to co-operate with rollers 16 when the rollers 14 are moved along the tracks to permit the door to open, as shown in dotted lines in Fig. 3.

To open the doors, it is only necessary to raise the pawl and operate the hand-wheel so as to cause the rollers 16 to travel from the position shown in full lines in Fig. 3 to the position shown in dotted lines in said figure, when the weight of the door will cause the door to drop to the position shown in dotted lines, in which position the rollers 16 are at their extreme lower limit of movement. To close the doors, the direction of movement of the hand-wheel 5 is reversed, causing the rollers 14 to move in an opposite direction on their tracks, in which event the rollers 16 will ride under the inclined surfaces of the plates 17 until the doors are closed, the final movement causing the rollers 16 to be located well under the horizontal portions of said bearing-surfaces and also upon the horizontal portion of the track 15, in which position the rollers 16 are at the extremity of their closing movement. Due to the fact that in operation the rollers 14 and 16 rotate in opposite directions one or both sets should be loose on the shaft 13.

While I have shown the mechanism as applied to two doors, it is obvious that a greater number of doors could be operated from the same power-shaft 4—as, for instance, if the car was provided with four doors the power-shaft could be located between two trans-

versely-arranged pairs of doors. The object of gearing down from the shaft 4 is to multiply the power derived from the hand-wheel 5.

I am aware that minor changes in the construction, arrangement, and combination of the several parts of my device can be made and substituted for those shown and described without departing from the nature and principle of my invention.

Having thus described the invention, what is claimed as new, and desired to be secured by Letters Patent, is—

1. In a car-door-operating mechanism, the combination with doors located on opposite sides of the center sills of the car, of a shaft extending across the car and provided with sets of rock-arms, links connected to said rock-arms, a reciprocating shaft mounted in the opposite ends of each set of links, tracks 15 cooperating with the ends of said reciprocating shaft, rollers on said reciprocating shaft cooperating with said doors, gearing located between the center sills of the car for driving the shaft which carries the rock-arms, and

means extending to one side of the car for operating said gearing; substantially as described.

2. In a car-door-operating mechanism, the combination of a driving-shaft 4 having a pinion mounted thereon, a shaft 10 having a gear-wheel 9 meshing with the pinion on the first-mentioned shaft, rock-arms on the shaft 10, links 12 connected to said rock-arms, a shaft 13 mounted in the ends of links 12, rollers 14 on the ends of shaft 13, tracks 15 with which said rollers coöperate, rollers 16 carried by the shafts 13, and a hinged door provided with a bearing-surface 17 for coöperating with said rollers 16; substantially as described.

In testimony whereof I hereunto affix my signature, in the presence of two witnesses, this 29th day of December, 1905.

JULIUS C. HERRMANN.
